Attorney.

UNITED STATES PATENT OFFICE.

RUDOLPH STURM, OF ST. PAUL, MINNESOTA.

DESIGN FOR A BRACELET, NAPKIN-RING, OR ARTICLE OF A SIMILAR NATURE.

58,409.

Specification for Design.

Patented July 12, 1921.

Application filed October 7, 1918. Serial No. 257,269. Term of patent 7 years.

To all whom it may concern:

Be it known that I, RUDOLPH STURM, a citizen of the United States, residing at St. Paul, county of Ramsey, and State of Minnesota, have invented a new, original, and ornamental Design for Bracelets, Napkin-Rings, and Articles of a Similar Nature, of which the following is a specification, reference being had to the accompanying drawings, forming part thereof.

Figure 1 is a perspective view of a bracelet or napkin ring, showing my new design.

Fig. 2 is a cross section of the same.

The drawing illustrates my ornamental design of a bracelet or napkin ring A, which is circular in shape. The bracelet A is formed of any suitable resilient material, having overlapping ends B and C.

The body portion D of the bracelet A car-

ries a strip E of red, a strip F of white, and a strip G of blue on its outer surface, giving the national American colors, red, white and blue about the outer face of the body portion of the bracelet. The red, white and blue stripes extend about the entire body portion of the bracelet A, and to the end of the portion B.

On the end C, which overlaps the end B of the bracelet A is a design of the American eagle with outspread wings in a blue field in which are thirteen stars. The stars are positioned in the blue field, six under each wing of the eagle and one star above the eagle.

I claim:

The ornamental design for a bracelet, napkin ring, or article of a similar nature, as shown and described.

RUDOLPH STURM.
